UNITED STATES PATENT OFFICE

138,301

DESIGN FOR A WOVEN TEXTILE FABRIC

John L Walther, New York, N. Y.

Application December 9, 1943, Serial No. 111,964

Term of patent 7 years

(Cl. D92—1)

To all whom it may concern:

Be it known that I, John L Walther, a citizen of the United States of America, residing in New York city, county of New York, and State of New York, have invented a new, original, and ornamental Design for a Woven Textile Fabric, of which the following is a specification, reference being had to the accompanying drawing, forming part thereof.

The figure on the drawing is a plan view of a woven textile fabric showing my new design.

The characteristic features of my design re-

side in the combination on the specific background shown of stripes as shown in which the wider stripe is composed of two narrow continuous contrasting stripes separated by a rope-like stripe of a second color, the two narrow continuous stripes above are of the same color as the narrow rope-like stripes separating the wider stripes.

I claim:

The ornamental design for a woven textile fabric, substantially as shown and described.

JOHN L WALther.
